UNITED STATES PATENT OFFICE.

FRANK J. LYNCH, OF HUNTINGTON PARK, CALIFORNIA.

ELEVATOR.

Application filed March 4, 1926. Serial No. 92,147.

- This invention relates to elevators and more particularly to elevators for raising or lowering sucker rods or other work in oil wells, and the general object of the invention is to provide a support for the elevator jaws when they are bridging the work-receiving recess of the elevator body to confine the work within said recess, thus preventing the jaws from being bent or broken.
10. A more particular object is to provide an elevator of the character stated which may be easily manipulated and readily applied to or disengaged from the work.
- With the above and other objects in view, 15 the invention consists in the novel and useful provision, formation, combination, association and relative arrangement of parts, members, and features, all as hereinafter described, shown in the drawings, and finally 20 pointed out in claims.

In the drawings:

Figure 1 is a side elevation of the elevator;

Figure 2 is a transverse vertical section of the elevator taken on the line 2—2 of Fig. 4; 25 Figure 3 is a transverse vertical section of the elevator taken at right angles to Fig. 2 on the line 3—3 of Fig. 5;

Figure 4 is a plan view of the elevator with its top plate removed and its jaws in 30 open position;

Figure 5 is a plan view of the elevator with its top plate removed and its jaws in closed position.

Corresponding parts in all the figures are 35 designated by the same reference characters.

Referring with particularity to the drawing, B designates a cup-shaped body formed with a vertical cylindrical wall b and a bottom wall b', on the top of which vertical wall 40 a top plate 1 is bolted by bolts 2, there being a work-receiving recess R in the vertical wall b and bottom wall b' of the body B and in the top plate 1, which recess extends radially from the center of the elevator through the 45 periphery thereof, and the inner end of the recess is struck on an arc from said center. The bottom wall b' has a rearward extension b'' and the top wall 1 has a rearward extension 1'. A circular cam disk D is turn- 50 ably fitted within the cylindrical wall b of the elevator body B upon the bottom wall b' of said body, said disk being provided with a radial recess r' extending from its center through its periphery, and there being a 55 handle H on the disk extending outwardly from the periphery thereof through a hori-

zontal slot b³ in the cylindrical wall of the elevator body. A latch L is pivoted at 3 to the outside of the vertical wall b of the body B and is formed with a shoulder 4, for engaging the handle H to hold the cam disk D against turning to the right when said disk is swung to its extreme position to the left.

A pair of arcuate jaws J rest upon the cam disk D and are pivoted at their rear ends at the rear end of the recess R on a pivot pin P secured at its upper end in a boss 1^b in the top plate 1, said jaws being formed respectively with knuckles j at the rear ends which rest one upon the other and through which depends the pivot pin P. In the lower sides of the jaws J are secured cam pins c which engage cam grooves C in the upper face of the cam disk D. The upper inner edges of the jaws J are beveled to form a conical seat S for the bell s' of a sucker rod s.

Trunnions T project from opposite sides of the body B and are engaged by the usual links K through which the elevator is raised 80 or lowered in the usual manner.

The operation of the elevator is as follows:

When the handle H is swung to the right to the end of the slot b³, the disk D is correspondingly turned until its recess r registers with the work recess R of the elevator body B, while the cam grooves C engage the cam pins c and swing the jaws open as illustrated in Fig. 1. In this position of the parts the work such as a sucker rod s is introduced into the recess R. The handle H and disk D are then swung to the left until that portion of the disk at the left side of the disk recess r, indicated r', is extended across the work recess R and said portion rests upon the bottom body wall b' at opposite sides of the work recess, during which operation the jaws J, by the engagement of cam grooves C with cam pins c, are swung closed around the sucker rod s, with the forward meeting ends of the jaws bridging the recess and resting directly upon the portion r' of the disk D, in which position the parts are locked by the engagement of the latch L with the handle H. The seat S of the jaws J engages the bell s' of the sucker rod s for raising or lowering the rod, and the disk portion r' supports the bridging ends of the jaws with the weight of the sucker rod 100 on the jaws and prevents breaking or bending of said ends of the jaws downwardly.

The extension 1^a and b" prevent the handle H from striking against objects, thus protecting the handle.

It is obvious that various changes and 5 modifications may be made, in practicing the invention, in departure from the particular showing of the drawing, without departing from the true spirit of the invention.

Having thus disclosed my invention, I 10 claim and desire to secure by Letters Patent:

1. In an elevator of the character as described, a body provided with a work-receiving recess, a cam disk turnably mounted in 15 said body and provided with a recess adapted to register with said work-receiving recess to permit the work to enter the same, the disk being arranged so that when turned a portion thereof may extend 20 across said recess with the work therein, a pair of work-holding jaws, and means actuated by said disk for swinging said jaws to bridge said work-receiving recess about the work therein and to rest upon said disk portion when 25 extended across said recess.

2. In an elevator of the character as described, a body provided with a work-receiving recess, a cam disk turnably mounted in said body and provided with a recess 30 adapted to register with said work-receiving recess to permit the work to enter the same, the disk being arranged so that when turned a portion thereof may extend across said recess with the work therein, a pair of 35 work-holding jaws, means actuated by said disk for swinging said jaws to bridge said work-receiving recess about the work therein and to rest upon said disk portion when extended across said recess, and means for 40 locking the disk with its portion extended

across the work-receiving recess and with the bridging ends of the jaws resting upon said extended disk portion.

3. In an elevator of the character as described, a body provided with a work-receiving recess, a cam disk turnably mounted in 45 said body and provided with a recess adapted to register with said work-receiving recess to permit the work to enter the same, the disk being arranged so that when turned a portion thereof may extend across said recess with the work therein, a pair of work-holding jaws, pins on said jaws and cam 50 grooves in said cam disk engaged by said pins for swinging said jaws to bridge said work-receiving recess about the work therein, and to rest upon said disk portion when 55 extended across said recess.

4. In an elevator of the character as described, a cup-shaped body, a top plate detachably secured on the top of said body, the body and top plate having a work-receiving recess therein, a cam disk turnably mounted in the bottom of said body and provided with a recess adapted to register with said 60 work-receiving recess to permit the work to enter the same, the disk being arranged so that when turned a portion thereof may extend across said recess with the work therein, a pivot pin depending from said top plate, a pair of work-holding jaws pivotally mounted on said pin and resting on said disk, and means actuated by said disk for 65 swinging said jaws to bridge said work-receiving recess about the work therein and to 70 rest upon said disk portion when extended across said recess.

In testimony whereof, I have signed my name to this specification.

FRANK J. LYNCH.
